Application January 8, 1954, Serial No. 403,024

9 Claims. (Cl. 103—178)

The present invention relates to a new suction pump which is especially adapted for drinking water wells.

Much has been done in connection with suction and impelling pumps, but as is known, these essentially comprise a cylinder in which a plunger is moved by means of adequate mechanism, said piston alternately dividing the cylinder into aspiration and impulsion chambers; in the aspiration run the plunger creates a vacuum such that the exterior atmospheric pressure is in condition to raise a valve allowing liquid to pass to the space left by the plunger. At the same time, the liquid existing in the other part of the cylinder closes the piston impulsion valve and this expels the liquid externally.

On reaching the dead point, the piston commences to retrocede, causing an increase in pressure in the aspiration chamber so that it closes the suction valve and opens the impulsion valve until the piston reaches the other dead point, all the water previously suctioned passing to the impulsion chamber so that, on commencing a new cycle, the impulsion valve is closed; and this cycle continues indefinitely.

The adjustment between the body of the pump and the respective plunger, generally composed of leather sheets, after a certain time of use, causes a certain amount of light to be seen between the contact surfaces, sufficient to cause seepage; and use of burlap causes a reduction in the rendering of the equipment.

In addition, the pump being provided with switch valves, the reduction of the hydraulic rendering is further increased. In this regard, poor adjustment of the said valves prevents the proper working thereof, and the closing of the passage of liquid is far from being efficient.

All these inconveniences have been overcome by the use of the invention to which the present application refers.

For this reason and in order that the system, based on the principle of two columns, renders really desirable results, it is necessary to provide a suction pump having a perfect adjustment between the cylinder and the respective plunger, as well as between all the displaceable means which must carry packings. When this is done, a practically perfect suction is obtained. The packings are constituted by elastic tubular jackets against which the rings which surround the plunger are strongly frictioned. This friction is facilitated by the auto-lubrication provided by the liquid being pumped.

Another object of the invention is to offer a new suction pump characterized by having a plunger composed of a cylinder with open extremes, alternatively closed by a disk secured to a stem, so that on aspiration the disk closes the lower open extreme of the cylinder, expelling the water in the upper portion of the pump. On the return stroke, the lower end of the cylinder is opened to permit the entrance of liquid thereto, and since the member which engages the upper end of the cylinder is slotted, the pump of the invention performs constant work upon two columns of liquid.

Another object of the invention is to provide a friction

2

pump with a valvular mechanical system, with its corresponding piston, adjusted in accordance with the technical directions previously mentioned, the stem of which is tensioned by a spring of sufficient capacity for closing the liquid inlet, in a smoothly and efficient manner, co-actioned by a cam prepared for that purpose.

Still another object of the invention is to offer a new suction pump constituted by a plurality of pump bodies, the respective plungers of which are actioned simultaneously by means of an appropriate mechanism, the positions of the various plungers, in their respective runs, correspond to different antagonistic positions, so that a continuous suction is obtained, bringing as a consequence the uninterrupted upward movement of the column of liquid suctioned commencing from the moment that the intakes of liquid, one for each pump body, are connected with a general intake.

Further objects and advantages of the present invention will become evident from the following description taken in conjunction with the accompanying drawings in which:

Fig. 1 is an elevation view of a section which shows a pump body constructed in accordance with the invention.

Fig. 2 is a partial view of one of the phases of the cam corresponding to the position of the pump of Fig. 1.

Figs. 3, 4 and 5 are sketches of the following consecutive phases of the complete cycle which corresponds to the positions of the pumps of Fig. 6, and finally

Fig. 6 is an elevation view, in section, of a device for carrying out the invention provided with three pump bodies constructively and operatively related to each other and provided with various plungers and admission valves.

In the different figures the same reference numbers indicate like or corresponding parts, letters indicating the whole of the various elements.

Referring to Fig. 1, *d* is a pump in accordance with the invention having a cylindrical pump body *a* within which a plunger *b* reciprocates. The pump body *a* comprises a central portion 1 and upper and lower portions 2 and 3 of enlarged internal diameter. Elastic tubular jackets 4 and 5, preferably made of rubber, are positioned to cover the internal surfaces of the portions 2 and 3 respectively.

A cylindrical tube 6 is provided within pump body *a*, said tube being frictionally secured to the jacket 4 at the upper portion 8 of the tube 6 by means of rings 7. Similar rings secure the bottom of the tube 6 to the jacket 5.

The plunger *b* comprises a stem 10, at the lower end of which is secured a disk 11 which closes the lower open end 12 of the tube 6. Rings 15 are secured to the upper end of the stem 10, the rings 15 being in continuous contact with an elastic tubular packing 16 which covers the internal surface of a coaxial tube 17.

A member 18 closes the top of the pump cylinder *a*, the member 18 having an orifice 19 which serves as a guide for the stem 10.

When the stem 10 is forced downwardly, it carries with it the spider 20, said spider 20 being secured to the stem 10 at 22 and carrying arms 23 which contact the upper edge 21 of the tube 6 so that the stem 10 forces the tube 6 downwardly. It will be observed that the spider 20 is spaced from the disk 11 by a distance which is greater than the length of the tube 6. Thus, when the arms 23 of the spider 20 contact the edge 21, the disk 11 is spaced from the tube 6 opening the lower open end 12 which remains open as the tube 6 is forced down by the stem 10.

The lower end of pump body *a* is connected to a tube 24 through which liquid enters the pump. An admission valve *c* comprising a disk 25 is provided for opening and

closing the tube 24. The disk 25 is formed at the end of lateral projection 26 which is fixedly secured to the lower end of plunger 27 which reciprocates within cylindrical housing 30 which is positioned alongside the pump body *a*. The interior of the housing 30 is lined with a tubular flexible packing 29 and the plunger 27 has rings 28 fixed thereto, said rings 28 sliding against the packing 29.

The plunger 27 is fixed to the lower end of a stem 31, said stem being guided by the member 33 and the aperture 33 in the top of the housing 30.

A stop 35 is secured to the lower end of the stem 31 beneath the member 33 and a compression spring 34 is placed on the stem between the member 33 and the stop 35 to urge the stem downwardly.

The upper end of stem 31 is formed with a guideway 36 through which axle 37 projects. Axle 37 rotates in bearings 38 and 39, power being supplied by a pinion 41 which meshes with gear 40 which is secured to the axle 37. A connecting rod 42 is secured at its upper end 43 by means of pin 44 to the side of gear 40 in an off-center position so that rotation of gear 40 raises and lowers the rod 42. The lower end of connecting rod 42 is formed with a yoke 45 which is pivotally secured to the head 46 of the stem 10. Thus, rotation of gear 40 effects vertical reciprocation of the plunger *b*.

A cam member 47 is secured to the axle 37 adjacent the guideway 36 at the upper end of stem 31. A pin 50 is secured to the stem 31 above the guideway 36 and a roller 49 is mounted on the pin 50 for free rotation. The cam 47 underlies the roller 49 with the periphery 48 of the cam 47 in close contact with the roller. Thus, rotation of the axle 37 revolves the cam 47 which raises the roller 49 to thereby overcome the pressure of spring 34 and lift the plunger 27 and hence the disk 25 of admission valve *c*. Since cam 47 functions only to lift the roller 49, it is not necessary for the periphery 48 of the cam 47 to maintain contact with the roller 49 throughout the revolution of the cam. As can be seen in Figs. 2, 3, 4 and 5, the cam 47 only contacts roller 49 over the portion of its periphery covered by the points 53, 54, 55 and 56.

Fig. 6 shows the invention using three of the pumps *d* each of which are identical to the pump *d* shown in Fig. 1, the various inlet tubes 24 being connected to a common main inlet 58 by means of the main channel 57. Each of the pumps *d* in Fig. 6 is powered by a common drive, as shown, so that all of the pumps *d* are operated simultaneously. However, the pumps *d* in Fig. 6 are not operated in phase with one another so that one of the pumps *d* is always creating a vacuum in the zone 3 so that the ascension of the column of liquid being drawn upwardly in the common main inlet 58 is not interrupted.

Function

When stem 10 raises the disk 11, it closes the opening 12 dragging in its ascending movement the cylindrical tube 6 which, operating as a piston produces a vacuum in the lower zone 33 of the body of pump *a*, whilst simultaneously, by pressing part 53 of the cam 47 against the roller 49 (Fig. 4) commences to elevate stem 31 with the admission valve *c* as may be seen in Fig. 6 (third body of the pump). When point 54 of cam 47 is reached, cam 47 is able to maintain roller 49 in a lifted position overcoming the tension of spring 34 along the original circumferential segment 54 and extreme 55, so that plunger 27 is maintained in such a position that the disk 25 opens the entrance 24 for the liquid. Owing to said existing depression in the inferior part of pump *a* the liquid suctioned by mouth 24 fills said inferior zone as may be seen in Figs. 1 and 2 (first body of pump Fig. 6). When stem 10 reaches the maximum limit of its run in an ascending movement, the descending movement is initiated (second body of pump Fig. 6) and stem 10 forces downward disk 11, uncovering the opening 12, as cylinder

der 6 is retained by the friction of rings 7 with their respective jackets 4 and 5. Simultaneously roller 49 has found a reduced space through the periphery 55-56 where cam 47 does not keep said roller 49 in its position 51 (Fig. 5), so that spring 34 carries it gradually to position 52 in accordance with said periphery; in this manner it allows stem 31 to descend, with which also causes descent of disk 25, on the entrance of liquid 24. On the other hand plunger *b* pursues its downward run whilst cam 47 in its rotation has freed roller 49, this position being maintained by the spring 34. (Figs. 3 and 2 of the pump body Fig. 6.)

Owing to the fact that the entrance 24 remains closed and the opening 12 is uncovered during the descending run of stem 10 and disk 11, the cylindrical tube 6 is carried by the spider 20, the liquid passing to the interior of cylinder 6.

When again the ascending movement of stem 10 is initiated, closing the opening 12, the liquid contained in the cylindrical tube 6 flows through the lateral opening 14.

The positions of cam 47 in Figs. 2, 3 and 4 corresponding to the 1st, 2nd and 3rd bodies of the pump in Fig. 6, respectively, are taken at the same moment, that is, when the first pump has reached its superior dead point, and the third pump has commenced its continuous suction operation.

Owing to the perfect manner in which are adjusted the tubular joints on the corresponding solidary rings to the mobile parts of the pumps, in order to effect the suction operation of the parts destined for hermetically sealing the openings communicating with the exterior, the pump of the present invention is able to render a high yield.

It is obvious that in carrying out the present invention, modifications of detail and structure of the specified device may be introduced, without this implying a departure from the scope of said invention, the characteristics of which are clearly stated in the following claims.

We claim:

1. A suction pump comprising a cylindrical pump body, a cylindrical tube positioned concentrically within said body for vertical reciprocation therein, rings mounted at the upper and lower exterior of said tube for frictional engagement with the interior of said body, a stem, a disk secured to the lower end of said stem and capable of closing the lower end of said tube, a spider mounted on said stem above said tube, said disk being spaced from said spider a distance greater than the length of said tube so that when said spider bears against the upper end of said tube, said disk is spaced from the lower end of said tube, an inlet for liquid positioned beneath said pump body, an outlet for liquid positioned above said pump body, valve means for said inlet for liquid; and mechanical means for opening and closing said said valve means in timed relation to the vertical reciprocation of said tube.

2. A suction pump as recited in claim 1 in which said valve means comprises a disk overlying said inlet and said mechanical means for opening and closing said valve means comprises a reciprocating plunger.

3. A suction pump as recited in claim 2 in which said reciprocating plunger is cam actuated and spring biased in a downward inlet closing direction.

4. A suction pump as recited in claim 3 in which said stem and said cam are actuated by a common drive.

5. A suction pump as recited in claim 4 in which said stem is secured at its upper end to a gear at a point spaced from the center of said gear, said gear being secured to an axle which passes through an opening in the upper end of said reciprocating plunger, a cam carried by said axle adjacent the upper end of said plunger, a roller mounted for free rotation on said plunger above said opening, said roller overlying the periphery of said cam.

6. A suction pump as recited in claim 1 in which said

cylindrical pump body comprises a central zone having a diameter greater than the diameter of said tube and upper and lower zones having a diameter greater than the diameter of said central zone.

7. A suction pump as recited in claim 6 in which said upper and lower zones are internally lined with elastic tubular jackets and said rings bear against said jackets.

8. A suction pump as recited in claim 1 in which a plurality of suction pumps are employed, each of said pumps having its inlet connected to an upwardly extending common inlet for liquid and said tubes are simultaneously reciprocated so that at least one of said tubes is being drawn upwardly at all times to prevent

interruption of the upward flow of liquid in said common inlet.

9. A suction pump as recited in claim 8 in which said plurality of suction pumps are operated with a common drive.
